Felix P. Kinsley, St. Louis, Mo.

Application August 6, 1945, Serial No. 121,264

Term of patent 14 years

(Cl. D45—15)

To all whom it may concern:

Be it known that I, Felix P. Kinsley, a citizen of the United States, residing at the city of St. Louis, State of Missouri, have invented a new, original, and ornamental Design for Pendant or the like, of which the following is a specification, reference being had to the accompanying drawing, forming part thereof.

Fig. 1 is a front elevational view of a pendant showing my design;

Fig. 2 is a top edge view; and

Fig. 3 is a side edge view thereof.

I claim:

The ornamental design for a pendant or the like, as shown.

FELIX P. KINSLEY.
